UNITED STATES PATENT OFFICE.

THOMAS L. FAWICK, OF WATERLOO, IOWA.

WATER-TUBE BOILER.

1,267,528.

Specification of Letters Patent.

Patented May 28, 1918.

Application filed May 7, 1917. Serial No. 166,905.

To all whom it may concern:

Be it known that I, THOMAS L. FAWICK, a citizen of the United States of America, and a resident of Waterloo, Blackhawk county, Iowa, have invented certain new and useful Improvements in Water-Tube Boilers, of which the following is a specification.

My invention relates to improvements in water-tube boilers, and the object of my improvement is to so form and mount a plurality of such tubes as to greatly enhance their efficiency in quickly producing steam, conserving a maximum amount of the heat units supplied thereto by the processes of combustion.

This object I have accomplished by the means which are hereinafter described and claimed, and which are illustrated in the accompanying drawings, in which Figure 1 is a vertical section of a furnace containing my improved water-tube boiler, taken on the broken line 1—1 of Fig. 2, looking in the direction indicated by the arrow; Fig. 2 is a cross section of said furnace taken on the broken line 2—2 of said Fig. 1, looking in the direction of the arrow, the boiler being shown in elevation taken at an angle of ninety degrees from that shown in Fig. 1; Fig. 3 is an enlarged detail section across some of the boiler-tubes of a modified form, and Fig. 4 is an enlarged fragmentary view of a part of one of the boiler-tubes, with a part broken away to display the method of mounting a head of said tube therein.

Similar numerals of reference denote corresponding parts throughout the several views.

Each tube 1 is drawn seamless steel tubing and longitudinally corrugated by a plurality of corrugations 2 which may be relatively low as shown, or given any desired altitude or angularity. These tubes are placed in parallel relation to each other, with relatively narrow interspaces, and may be positioned in any desired manner, but preferably set upright, or slightly tilted as illustrated, and may be supported in any way, without departing from the principle of my invention.

I prefer, however, to provide a relatively large number of like rectangular plates 4, having pluralities of convoluted slots to correspond with the number of water-tubes used, the tubes being tightly fitted into the slots in said plates, the plates regularly

spaced apart along the tubes throughout their entire lengths. By this means, all the tubes are supported and securely bound together in the necessary relations to furnish narrow winding or convoluted passages between them and between the plates through which may freely pass transversely the heated gases of combustion.

The tubes are closed at each end by plates 3 fitted tightly thereto and electrically welded therein, as shown in Fig. 4.

The boiler is mounted in an inclined position within a fire-box or furnace 6, having a fire-brick lining 5 to conserve heat, said furnace having a flue 7, and may have any desired means for producing combustion beneath the boiler.

A pipe 8, located across the combustion-chamber has a plurality of short tubes 9 which deliver to the lower ends of the tubes 1 at their lowest point, as shown in said Fig. 1, while a pipe 10 crosses the upper part of the furnace above the flues, receiving steam from the uppermost angles of the flues, by way of short communicating tubes 11. This method of tilting the tubes, and placing the inlet- and outlet-ports at the lowermost and uppermost angles of the ends of the tubes, causes a direct circuit through the tubes from their inlet- to their delivery-ports, makes tubes self-cleansing and equalizes their action in the production of steam.

The dotted line in Fig. 1 indicates the preferred water-level in the tubes, which may be maintained at a constant height by means of any suitable regulating appliance not shown.

The ends of the plates 4 are in contact with and are tightly secured between plates 12 mounted on the inner opposite walls of the furnace by means of bolts 13 which latter resist the outward thrust caused by high-pressure steam upon the tubes 1. The heated products of combustion pass through in convoluted passages between the boiler 2 and between said plates 4 and are evacuated from the furnace by way of the flue 7.

The plurality of plates 4 not only connect and support the tubes 1, but, since they become highly heated, convey much heat to the tubes, conserving heat units and utilizing them in producing steam. The corrugated tubes 1, by their corrugations 2 and related troughs, lengthen the passages between the tubes and this increases the ab-

sorption of heat to such a large extent as to render the boiler very rapid in accelerating steam production, especially at the beginning of the operation. This makes the 5 boiler very suitable for use in producing steam rapidly to actuate motors of vehicles.

The tubes 1 may be of any length, number, or have any kind of form desired to furnish convoluted flue-passages between 10 them.

Having described my invention, what I claim as new, and desire to secure by Letters Patent, is:

In a steam-boiler, a fixed combustion- 15 chamber having rigid walls, a plurality of spaced flattened water-tubes within and spaced from the walls of said chamber, a

plurality of spaced transverse plates having orifices in which said tubes are fitted, longitudinal plates engaged between opposite 20 ends of said plurality of plates parallel to the flattened sides of said water-tubes and the walls of said chamber, and bolts passed through said chamber walls and securing said longitudinal plates upon said transverse plates, the walls and longitudinal plates acting as abutments for the transverse plates and inclosed flattened water-tubes.

Signed at Waterloo, Iowa, this 2d day of May, 1917.

THOMAS L. FAWICK.
